COMBINATION HOUSE NUMBER AND DOOR-BELL UNIT

Chauncey W. Ferris, Ann Arbor, Mich.

Application March 11, 1946, Serial No. 127,331

Term of patent 3½ years

(Cl. D1—12)

To all whom it may concern:

Be it known that I, Chauncey W. Ferris, a citizen of the United States, residing at Ann Arbor, in the county of Washtenaw and State of Michigan have invented a new, original, and ornamental Design for a Combination House Number and Doorbell Unit, of which the following is a specification, reference being had to the accompanying drawing, forming part thereof.

In the drawing:

Fig. 1 is a front view shown slightly in perspective of a combination house number and doorbell unit, showing my new design, and

Fig. 2 is an end elevational view.

The essential features of my design reside in the portions shown in full lines.

I claim:

The ornamental design for a combination house number and doorbell unit, substantially as shown and described.

CHAUNCEY W. FERRIS.
